UNITED STATES PATENT OFFICE.

EMERICK HODALY, OF BAKERSFIELD, CALIFORNIA.

BROOM.

1,283,410.

Specification of Letters Patent. Patented Oct. 29, 1918.

Application filed April 3, 1917. Serial No. 159,514.

To all whom it may concern:

Be it known that I, EMERICK HODALY, a citizen of the United States, residing at Bakersfield, in the county of Kern and State of California, have invented certain useful Improvements in Brooms, of which the following is a specification, reference being had therein to the accompanying drawing.

The present invention relates to a broom, and has particular reference to a detachable handle to which the broom head may be secured.

It is an object of the present invention to provide a handle with an improved clamp adapted to be interchangeably engaged with broom heads so that the bunches of straw, when worn out, may be replaced and the same handle be employed indefinitely.

It is another object of the present invention to provide a broom of this type wherein the broom head is substantially braced so that the broom may be used for heavy work, such as in cleaning mud and the like from floors, and for use around barns, stables and the like.

The above and various other objects and advantages of this invention will be brought out in the following detailed description of the present preferred embodiment, the same being illustrated in the accompanying drawings, wherein—

Figure 1 is a side elevation of a broom constructed in accordance with this invention;

Fig. 2 is a transverse section taken through the lower portion of the broom;

Fig. 3 is a detail view of one of the jaws carried rigidly upon the handle;

Fig. 4 is a detail view of the removable jaw;

Fig. 5 is a side elevation showing a slight modification of the invention;

Fig. 6 is an edge elevation thereof;

Fig. 7 is a vertical transverse sectional view through the lower portion of the broom;

Fig. 8 is a detail view of one of the jaws carried rigidly upon the handle;

Fig. 9 is a detail view of the removable jaw.

Similar reference characters indicate corresponding parts throughout the several views of the drawings.

Referring to this drawing, 10 designates a handle which may be of any length and size desired, and which is provided upon its lower end with a fixed ferrule 11 adapted to carry one of the jaws of the device. This fixed jaw comprises an intermediate arm 12 which is bowed outwardly to a slight extent and which extends downwardly for engagement against one side of the broom head 13. The fixed jaw also includes the end arms 14 which are bowed outwardly and downwardly from the ferrule 11 and are adapted for engagement against the opposite ends of the broom head 13. The lower ends of the arms 12 and 14 are connected together by means of a strap 15 which, when the broom is in upright position, extends substantially horizontally across the lower ends of the arms to connect the same and provide a substantially rigid jaw. A spring arm 16 is mounted on the intermediate arm 12 and is sprung inwardly to a slight extent and provided upon its lower end with a toothed foot 17 adapted for binding engagement against the broom head 13. The lower extremities of the end arms 14 are provided with in-turned spring fingers 18 which bite into the opposite ends of the head 13 and are used for a purpose which will hereinafter appear.

The detachable jaw adapted for engagement against the opposite side of the broom head 13 comprises an upwardly tapering shank 19 which is relatively flat and curved, and adapted to lie against and to conform to the outer surface of the ferrule 11. The lower end of the shank 19 is provided with an outwardly bowed intermediate arm 20 provided with a plurality of inwardly and downwardly extending spring arms 21 having feet 22 thereon which may be provided with teeth for binding engagement with the broom head. The shank 19 also carries a pair of end arms 23 which are offset inwardly from the shank to fit beneath the ferrule 11, and which are bowed outwardly and downwardly to engage against the opposite ends of the broom head to abut against the edges of the arms 14 of the fixed jaw. A horizontal strap 24 connects the lower ends of the arms 20 and 23 and provides therewith a substantially rigid structure. The lower ends of the arms 23 have inwardly inclined fingers 25 adapted for engagement

behind the spring fingers 18 of the fixed jaw in order to hold the lower end of the movable jaw in position against the broom head.

- 5 In application, the broom head 13, which comprises the usual bunch of straws suitably united together in the form of an ordinary broom head, is placed within the fixed jaw against the spring-held foot 17, and forced 10 into the fixed jaw by engagement of the detachable jaw against the opposite side of the broom head. The shank 19 is placed against the ferrule 11, and the sleeve or ring 26 is slid downwardly over the ferrule and 15 the shank 19, drawing the latter tight against the ferrule and binding the detachable jaw against the fixed jaw. If desired, the horizontal strap 15 of the fixed jaw may be provided with a plurality of inwardly extending 20 teeth for biting engagement in the adjacent side of the broom head to hold the latter from slipping out of place when the jaws are forced together. After the jaws are brought together, the fingers 18 are 25 sprung outwardly over the fingers 25 to interlock the lower ends of the jaws and thus securely hold the broom head to the handle. The above described structure is such that the broom head is braced and the connection 30 between the broom head and the handle is reinforced to prevent breakage of the connection therebetween. When the bunch of straws is worn out the sleeve 26 may be readily raised upon the ferrule 11 and the 35 fingers 18 released from the fingers 25, permitting the removal of the removable jaw and the application of a new broom head to the handle. If desired, the fingers 18 may be rigid and the fingers 25, which are shown 40 curved downwardly, be inserted behind the inturned ends of the fingers 18, the latter acting as a fulcrum or pivot upon which the detachable jaw may be swung upwardly into position.
- 45 The bunch of straws 13 may be held together at its upper end by a coarse mesh fabric 27 to bind the upper ends of the straws tightly together and provide a firm hold for the spring-pressed feet carried by 50 the jaws.
- 55 In Figs. 5 to 9, inclusive, there is shown a modified form of the invention, wherein the handle 28 carries at its lower end the ferrule 29, which is provided with a fixed jaw comprising the arms 30 which extend in divergent relation from the ferrule 29 and are integral with a cross bar 31 which is adapted to lie substantially horizontally across the body of the broom 32, and these 60 arms and bar constitute a rigid jaw. Co-operating with the rigid jaw is a detachable jaw comprising an upwardly tapered shank 33 integral with downwardly divergent arms 34 and a cross bar 35 which is formed with

the arms, the shank 33 being relatively flat 65 and curved and is adapted to lie against and conform to the outer surface of the ferrule 29.

The extremities of the bar 31 are provided with inturned spring fingers 36, while the 70 bar 35, at the extremities thereof, is formed with inwardly inclined fingers 37 adapted for engagement of the spring fingers 36 on the fixed jaw in order to hold the lower end of the movable jaw in position against the 75 broom body 32 when the detachable jaw is clamped in working relation to the fixed jaw in a manner presently described. Slidable over the ferrule 29 is a clamping ring or collar 38 which engages with the shank 33 80 of the detachable jaw, and in this manner the latter is fastened for co-action with the stationary jaw for the clamping of the broom body 32 between said jaws, the broom body being readily detachable or removable 85 when worn out, and this is accomplished by raising the collar 38 out of engagement with the shank 33, permitting the removal of the detachable jaw and the application of a new 90 broom body to the handle. It will be apparent that the broom body 32 will be firmly clamped or held fast between the fixed and detachable jaws of the device for the use 95 thereof in the ordinary well known manner.

It is, of course, understood that various 9 changes and modifications may be made in the structure of the above specifically 10 described embodiment of this invention without departing from the spirit thereof, and being restricted only by the scope of the following claim.

Having thus described my invention, I 11 claim:

In a broom, the combination with a handle, a ferrule mounted on the handle and provided with a fixed jaw including an intermediate arm bowed outwardly and extending downwardly and including also end arms which are bowed outwardly and downwardly, all of said arms terminating at their 1 lower ends in a strap provided with teeth on its inner face, the fixed jaw being further provided with inturned spring fingers formed at the lower ends of the end arms, a spring grip also provided with teeth and 1 carried by the said intermediate arm, a broom head fitting said fixed jaw, a detachable jaw having an upwardly extending tapering shank which is relatively flat and curved to conform to lie against the said 1 ferrule, the detachable jaw being formed with intermediate and end bowed and downwardly extending spring arms, the said end arms having feet for engagement behind the said spring fingers, a pair of spring grips 1 provided with teeth on their inner faces and mounted one above the other on the intermediate arm of the detachable jaw, and a

ring slidably mounted on the ferrule for engagement over the said tapering shank, whereby the two jaws are secured together with the broom head between them, the 5 spring grips on the detachable jaw being in staggered relation to the spring grip and the said strap on the fixed jaw, whereby the

broom head is firmly gripped on opposite sides thereof without having the gripping members engage the said head on directly 10 opposite sides.

In testimony whereof I affix my signature.

EMERICK HODALY.
